(57) **CLAIM**

The ornamental design for a concealed oval shower head as shown and described.

DESCRIPTION

1. Concealed oval shower head

1.1 : Front

1.2 : Top

1.3 : Right

1.4 : Bottom

1.5 : Perspective

1.6 : Enlarged

The design is an oval-shaped concealed shower head; Fig. 1.1 is a front view of the product; a shower head integrated in the ceiling, which may be varnished with the same colors of the ceiling and be finished in the same way, but still remains visible; the reproduction shows the profile of the three-dimensional oval-shaped shower head, which sticks out from the two-dimensional flat ceiling; in particular, from the top to the bottom, the reproduction shows a knob and, below, three parts on top of each other; the knob and the first part on the top, just under the knob, are not visible in the normal use of the product, as they are embedded in the ceiling, therefore, they are disclaimed; on the other hand, the parts visible in the normal use and for which registration is sought are: the second part below the knob (from the top to the bottom), that is the frame around the shower head, and, on the bottom, the walls of the shower head, both perpendicular to the ceiling; Fig. 1.2 is a top view of the product which shows: the top of the frame and, upon it, the oval top part with four curved ledges on the corners, with a knob in the middle; this reproduction is attached for clarity's sake only, as top parts are embedded in the ceiling and they are not visible in the normal use of the product, they are disclaimed; Fig. 1.3 is a right-side view of the product showing the same elements of Fig. 1.1; Fig. 1.4 is a bottom view of the product which shows, from outside to inside: the external frame, a darker oval line which is the slot between the frame and the walls of the shower head, a thicker and clearer oval line, which is the base of the shower head's walls, the shower head's inner walls, which are concave and

(Continued)

oval, the flatbed base of the shower head, with the nozzles; Fig. 1.5 is a perspective view of the product showing the same elements of Fig. 1.4; it better shows the three-dimensional shower head cover and the junction curve between the frame and the parts that stick out from it; Fig. 1.6 is an overview of the product showing the entire design of the installed product; it is evident how the frame integrates and disappears completely into the ceiling, highlighting the oval shape of the shower head.

The broken lines shown in the drawings illustrate portions of the article and form no part of the claimed design.
